ACCORDION SHIFT MECHANISM

Otto Schmidt, De Kalb, Ill., assignor to Wurlitzer
Grand Piano Company, De Kalb, Ill., a corpora-
tion of Illinois

Application September 16, 1935, Serial No. 40,667

8 Claims. (Cl. 84—376)

This invention relates to accordions and similar musical instruments, and is directed especially to manual means for operating or shifting the port-manual governing the tone quality of the music. One object of the invention is to provide such a mechanism in a simple, economical form, and another object is to arrange the mechanism so compactly that it shall occupy very little space without any sacrifice of efficiency. A further object is to ensure the location of the operating key or lever in a position which shall be particularly convenient so that its use shall not interfere with the playing of the manual keys, even though it may be actuated by the same fingers which are employed on these keys. The invention consists in certain features and elements of construction in combination, as herein shown and described and as indicated by the claims.

20 In the drawing:

Figure 1 is a fragmentary front elevation of a portion of the accordion keyboard and an adjacent wind-chest wall upon which the shift mechanism is mounted.

25 Figure 2 is a section taken substantially at the line 2—2 on Figure 1.

Figure 3 is a front elevation of the shift mechanism itself with the cover removed, and showing the parts at one limit of their movement.

30 Figure 4 is a section taken substantially at the same plane as Figure 2, but showing the parts at a position substantially midway between limits of the stroke.

Figure 5 is a section similar to Figure 4, showing the parts as positioned at the end of the working stroke.

Figure 6 is a front elevation of the shift mechanism with the parts in the positions shown in Figure 5.

40 One use of the shift mechanism of this invention is the actuation of slide valves or dampers such as are frequently employed in accordions for adding or eliminating a particular set of reeds to be sounded in conjunction with other reeds in varying the tone quality. Such slide valves are usually positioned just back of the wind-chest wall, 1, of which a fragment appears in Figure 1, and are interposed between the reed blocks, 2, and the ports, 3, in the wall, said ports being controlled by valves, 4, actuated by several keys, 5, of the manual. The slide valve itself, seen at 6, may be simply a plate having ports, 7, which are adapted to be registered with the ports, 3, and the several chambers of the reed block when the slide is shifted longitudinally from its closed

position in which the spaces between its ports, 7, close the respective chambers of the reed block. This slide valve structure, however, is merely an illustration of a device which may be actuated by the mechanism of my invention, and it may be understood that it may serve various other devices which are alternately adjusted in one direction and then in the other.

The shift mechanism itself is shown in Figure 1, enclosed under a cover, 10, of a casing having a back plate, 11, seen in Figure 2, and adapted to be secured to the wind-chest wall, 1, as by a screw 12. A rockable member in the form of a disk, 13, is carried on a pivot stud, 14, anchored in the back plate, 11, and steadied in an opening in the cover, 10. The member, 13, carries a crank pin, 15, which engages in a slot, 8, in the slide valve, 7, for actuating the latter when the disk, 13, is rocked. An arcuate clearance slot, 16, in the back-plate, 11, may serve to limit the extent of the rocking movement.

Extending directly over the manual keys I provide a finger-piece, 17, on a lever, 18, fulcrumed at 19 in suitable brackets, 20, projecting from the wind-chest wall, 1. The inner end, 21, of this lever engages a slidably mounted pusher, 22, guided for reciprocation between the side flanges, 23, of the casing, and held to a path substantially in contact with the back-plate by means of a guide lug, 24, projecting inwardly from the cover, 30 10. The pusher, 22, is formed with a transverse driving edge, 25, from which motion is transmitted to the rockable member, 13, through links, 26, which act alternately for this purpose to rock the member, 13, first in one direction and then in the other. Each link is provided with a terminal lug, 27, whose transverse edge, 28, is engageable with the driving edge, 25, of the pusher, 22; the parts are shown in position ready for such engagement in Figure 3.

Both lugs, 27, have portions, 29, which extend laterally across a common path along which they reciprocate, so that it is necessary for these portions to pass each other in some manner to avoid interference. Referring to Figure 3, it will be seen that as the pusher, 22, advances upwardly (on the drawing) engaging the lug, 27, of the right-hand link, 26, and thus rotating the member, 13, in counter-clockwise direction, the portion, 29, of this lug will meet the similar portion, 29, of the lug, 27, on the other link, which is caused to move in the opposite direction (that is, downwardly on the drawing) as the disk, 13, rotates. The edges of the parts, 29, which would otherwise collide, are beveled at 30 and 31 so that

40

45

50

55

as they meet, the beveled surfaces will act cam-wise to cause the downwardly traveling lug to ride up over the lug of the other link, 26, as seen in section in Figure 4. And as the movement 5 proceeds the lug will travel onto the surfaces of the pusher, 22, as seen in Figure 5. The other lug, 27, of the right-hand link, 26, will have remained substantially in the same plane as the pusher, 22, throughout the stroke, and by its engagement 10 with the driving edge, 25, of the pusher will have been carried to the position shown in Figure 6.

Now, upon release of the pressure from the finger-piece, 17, the retracting spring, 32, will swing the finger-piece up and draw the other end, 21, of the lever downwardly, at the same time 15 retracting the pusher, 22, to the lower limit of its movement, so that it will withdraw from under the lug, 27, of the left-hand link until its driving edge, 25, passes the edge, 28, of that lug. Both links, 26, are preferably of spring material, stressed to urge their terminal lugs, 27, toward the back plate, 11; hence, when the pusher, 22, has withdrawn from under the left-hand lug, 27, the latter will snap toward the plate, 11, into 20 position for encounter by the driving edge, 25, the next time the pusher, 22, is actuated. And such actuation will drive the left-hand link, 26, upwardly, thus rotating the disk, 13, in clockwise 25 direction, and returning the parts to their initial position illustrated in Figure 3. Upon such return movement the lug, 27, of the right-hand link, 26, will ride up over the part 29 of the left-hand lug by reason of the cam action of their beveled edges, 30 and 31. It will be understood 30 that other spring means than the links, 26, might be provided for ensuring the action just described, but the mechanism is kept simple and efficient by making these links of flat spring stock, 35 as indicated. The links and their terminal lugs are confined to their proper paths of reciprocation by the presence of the side flanges, 23, of the back-plate, 11, and by a guide post, 33, upstanding from the back-plate, 11, and serving incidentally to receive the screw, 34, by which the cover 40 plate, 10, is held.

The compactness of the shift mechanism embodied in the keys, 10, 11, is such that, if desired, this device can be mounted on the wind-chest 45 wall, 1, so as to occupy substantially no more width than one of the valves, 4, and with a piano-type keyboard it will be understood that there are naturally a number of gaps in the row of valves corresponding to the black keys; consequently, 50 several of these shift devices may be so located, if desired, for actuating various slide valves and other devices of the instrument, each shift being furnished with its own finger-piece, 11, projecting over the keyboard in convenient position for 55 actuation by the performer without materially shifting his hand from playing position without seriously interfering with his playing of the key manual.

While there is shown and described herein certain specific structure embodying the invention, it will be manifest to those skilled in the art that various modifications and re-arrangements of the parts may be made without departing from the spirit and the scope of the invention, and that 60 the same is not limited to the particular form herein shown and described, except in so far as indicated by the appended claims.

I claim:

1. A shift mechanism for accordions comprising a pivoted rocking member, a pusher guided

for reciprocation toward and from the pivot of the rocking member, and a pair of links pivotally connected to said member at opposite sides of its pivot, said pusher having a driving face or edge transverse to the direction of its reciprocation and each link having a lug with a transverse edge engageable with said driving edge of the pusher, said lugs having portions extending laterally across a common path with transverse edges beveled for engagement with each other to permit the lugs to pass each other by the cam action of said beveled edges, forcing the idle lug to ride onto and over the active lug and past the driving edge of the pusher while the latter is moving said active lug in the opposite direction. 15

2. A shift mechanism for accordions comprising a pivoted rocking member, a pusher guided for reciprocation toward and from the pivot of the rocking member, and a pair of links pivotally connected to said member at opposite sides of its pivot, said pusher having a driving face or edge transverse to the direction of its reciprocation and each link having a lug with a transverse edge engageable with said driving edge of the pusher, 20 said lugs having portions extending laterally across a common path with transverse edges beveled for engagement with each other to permit the lugs to pass each other by the cam action of said beveled edges, forcing the idle lug to ride onto and over the active lug and past the driving edge of the pusher while the latter is moving said active lug in the opposite direction, said pusher having a return stroke sufficient to withdraw its driving edge from under the idle lug, 25 and the lug being yieldingly urged against the pusher so that as the latter withdraws said idle lug will snap into the same plane as the pusher in position for active engagement thereby in the next driving stroke. 30

3. A shift mechanism for accordions comprising a pivoted rocking member, a pusher guided for reciprocation toward and from the pivot of the rocking member, and a pair of links pivotally connected to said member at opposite sides of its pivot, said pusher having a driving face or edge transverse to the direction of its reciprocation and each link having a lug with a transverse edge engageable with said driving edge of the pusher, 40 said lugs having portions extending laterally across a common path with transverse edges beveled for engagement with each other to permit the lugs to pass each other by the cam action of said beveled edges, forcing the idle lug to ride onto and over the active lug and past the driving edge of the pusher while the latter is moving said active lug in the opposite direction, each of said links being of spring material stressed for urging its lug against the pusher, and said pusher having a return stroke sufficient to withdraw its driving edge from under the idle lug, permitting 50 said lug to snap into the same plane as the pusher in position for active engagement thereby in the next driving stroke. 55

4. A shift mechanism for accordions comprising a pivoted rocking member, a pusher guided for reciprocation toward and from the pivot of the rocking member, and a pair of links arranged substantially parallel to each other and pivotally connected to said member at opposite sides of its pivot, guide means for confining the movements of said links and said pusher to approximately parallel paths, said pusher having a driving edge transverse to the direction of its reciprocation, and each link having a terminal lug with a transverse edge engageable with said driving 75

edge of the pusher, means for deflecting one lug out of the plane of movement of the other and of the pusher as they travel in opposite directions, whereby the idle lug is caused to ride past the driving edge of the pusher while the latter is moving said active lug in the opposite direction toward the pivot of the rocking member.

5. A shift mechanism for accordions comprising a casing with parallel lateral guide flanges, a rocking member pivoted in said casing, a pusher guided for reciprocation toward and from the pivot of the rocking member and between said flanges, and a pair of links pivotally connected to said member at opposite sides of its pivot; a guide post upstanding from the bottom of the casing between said links for engaging their inner edges, each of said links having a portion engageable with one of the side flanges for further guidance in substantially the direction of movement of the pusher, said pusher having a driving face or edge transverse to the direction of its reciprocation, and each link having a transverse edge engageable with said driving edge of the pusher, together with means for alternately guiding each of said links in its idle stroke out of the path of the pusher while the latter is actively moving the other lug in the opposite direction.

6. A shift mechanism for accordions comprising a casing with parallel lateral guide flanges, a rocking member pivoted on the back plate of the casing, a pusher guided for reciprocation toward and from the pivot of the rocking member and between said flanges, and a pair of links pivotally connected to said member at opposite sides of its pivot; a guide post upstanding from the back plate between said links for engaging their inner edges, each of said links having a portion engageable with one of the side flanges for further guidance in substantially the direction of movement of the pusher, said pusher having a driving face or edge transverse to the direction of its reciprocation, and each link having a transverse edge engageable with said driving edge of the pusher, together with means for alternately guiding each of said links in its idle stroke out of the path of the pusher by movement transversely of the plane of the back plate while the pusher is actively driving the other lug in the opposite direction,

and a cover plate for the casing enclosing said links and rocking member and extending substantially parallel to the back plate for limiting the deflection of the lugs away from the path of the pusher, said cover including guide means for 5 confining the pusher to its normal path adjacent the back plate.

7. A shift mechanism for accordions comprising a pivoted rocking member, a pusher guided for reciprocation toward and from the pivot of 10 the rocking member, and a pair of links pivotally connected to said member at opposite sides of its pivot, said pusher having a driving face or edge transverse to the direction of its reciprocation and each link having a lug with a transverse 15 edge engageable with said driving edge of the pusher, said lugs having portions extending laterally across a common path with transverse edges beveled for engagement with each other to permit the lugs to pass each other by the cam 20 action of said beveled edges, forcing the idle lug to ride onto and over the active lug and past the driving edge of the pusher while the latter is moving said active lug in the opposite direction, together with a crank pin extending from the 25 rocking member for transmitting motion therefrom, a manually operable lever engaged with the pusher for actuating the same in driving direction, and a return spring for effecting the idle 30 stroke of the parts.

8. A shift mechanism for accordions comprising a pivoted rocking member, a pusher guided for reciprocation toward and from the pivot of the rocking member, and a pair of links pivotally connected to said member at opposite sides 35 of its pivot, said pusher having a driving face or edge transverse to the direction of its reciprocation, and each link having a lug with a transverse edge engageable with said driving edge of the pusher, said lugs having portions extending laterally across a common path and formed to cam 40 upon each other as they pass, moving in opposite directions, whereby the idle lug is deflected out of the plane of movement of the active lug and the pusher, and is caused to ride past the driving edge of the pusher while the latter is moving 45 said active lug in the opposite direction.

OTTO SCHMIDT.
